UNITED STATES PATENT OFFICE.

WILLIAM A. MINOR, OF ROCHESTER, NEW YORK, ASSIGNOR TO LUITWIELER PUMPING ENGINE COMPANY, OF ROCHESTER, NEW YORK, A CORPORATION OF NEW YORK.

PUMP.

Application filed January 2, 1926. Serial No. 78,765.

The present invention relates to pumps and more particularly to the type in which the cylinder has an air chamber connected to the upper end thereof for the purpose of absorbing the fluctuations in the water delivery. An object of this invention is to prevent the water logging or filling of the air chamber with water in the event the air from the air cylinder leaks out. A further object of the invention is to provide a float controlled valve between the air chamber and the pump cylinder which will shut off the air chamber when the latter becomes ineffective due to the leakage of air therefrom.

Still another object of the invention is to provide means for draining the pump below a float controlled valve between the air chamber and the cylinder upon the stopping of the pump so that the air chamber may be refilled with air.

To these and other ends, the invention consists of certain parts and combinations of parts, all of which will be hereinafter described: the novel features being pointed out in the appended claims.

In the drawings:

Fig. 1 illustrates a fragmentary section of a pump constructed in accordance with this invention; and

Fig. 2 is a sectional view of the back pressure check valve.

Referring more particularly to the illustrated embodiment of the invention, 2 indicates a frame which has beneath it a discharge head 3 provided with an outlet portion 4 with which the discharge pipe 5 connects, said discharge pipe having therein a check valve 6 with its movable valve member 7 normally occupying a closed position. Secured to the discharge head 3 is the pump cylinder 8 in the form of tubes depending from the discharge head. This cylinder is in turn surrounded by the tubular casing 9. Within the cylinder 8 operates as usual two valve pistons or buckets, the lower one of which is operated through a rod (not shown) and extending upwardly through the upper piston or bucket and through the hollow rod 15 connecting with the upper bucket. This hollow rod is guided through a packing 16 on a plate 17 which closes the top of the discharge head 3. The operating mechanism for the rods may be of any suitable construction. Rising from the bottom plate of the frame 2 is an upright member 26.

In this type of pumps, it has been customary to provide an air chamber which communicates with the upper end of the cylinder to act as a cushion or absorbent for fluctuations in the water delivery. When this chamber is formed from cast iron, the air gradually leaks through the porous walls and as a consequence the chamber becomes filled with water or water logged, rendering the chamber not only useless, but an actual detriment in the operation of the pump as it accentuates the fluctuations in the water column.

In this invention, provision is made for closing off the air chamber as the water approaches the chamber, so that the accentuations of the fluctuations will not take place, provision being made for draining the pump above the check valve in the discharge pipe after the pump has ceased operation, while at the same time effecting the opening of the air chamber and permitting air to enter therein after the draining takes place.

In the illustrated embodiment of the invention the air chamber 37 is formed in the upright 26 which is provided at its lower end with an enlarged portion having a partition 38 therein. This partition has a passageway 39 about which a valve seat 41 is formed below the partition. With this valve seat, a valve member 43 cooperates, said valve member being mounted on a stem 44 guided in the partition 38. In the chamber 45 below the partition 38, a float 46 is arranged, this float being mounted on the stem 44, so that when the chamber 45 fills with water the float will rise and move the valve member 43 against the seat 41. The float 46 also acts as a weight to cause the valve member 43 to open, at the same time, permitting said valve member to move upwardly. A plunger 47 guided in the wall of the chamber 37 may be employed for engaging with the valve stem 44 in order to hold the valve member 43 open. The chamber 45 connects by a passageway 48 with the discharge head 3 so that the fluid pressure in the head provides compressed air in the passageway 48 and chamber 45 as well as in the compressed air chamber 37. Should water from the discharge head 3 pass by way of the passageway 48 to the chamber 45, it will act on the float 46 and move the valve member 43 toward the seat 41, closing the passageway between the chamber 45 and

the chamber 37, so that the pump will then act independently of the air chamber 37, but so as not to have its fluctuations accentuated. When the pump stops, the water in the chamber 45, passageway 48, head 3 and the upper portion of the cylinder 8 will be drained off by way of the leak port 49, the water which has been discharged from the pump being prevented from returning to the discharge head because the check valve 7 will automatically close. At the same time, air will be admitted to the chamber 45, passageway 48 and the discharge head, as well as to the chamber 37 by way of an air inlet passageway 50 which is normally closed by a valve member 51 and held closed by the air pressure within the chamber 45.

From the foregoing it will be seen that there has been provided a pump in which the column of water is subject to an air pressure in an air chamber at the upper end of this column, this air chamber having a valved connection with the cylinder of the pump and the valved connection being controlled by a float which will automatically shut off the air chamber in the event that the air chamber becomes useless. Provision is also made for draining the pump below the air chamber when the pump is stopped so that the valve may again open so as to provide communication between the air chamber and the cylinder, a check valve being provided in the discharge line of the pump so that water from the discharge line may not flow back into the pump cylinder during such drainage. Provision is also made for the admission of air to the air chamber and that portion of the pump above the drain opening upon the draining.

What I claim as my invention and desire to secure by Letters Patent is:

1. A pump comprising a cylinder, an air chamber at the upper end of the cylinder for absorbing the fluctuations in the water column of the pump, and means for automatically cutting off said air chamber from the cylinder when the water rises to a certain point in the system and before the chamber becomes ineffective as a fluctuation absorbent medium. 50

2. A pump comprising a cylinder, an air chamber connecting with the upper end of the cylinder for absorbing the fluctuations in the water delivery of the pump, and a float valve controlling the communication of the air chamber with the pump cylinder. 55

3. A pump comprising a cylinder, an air chamber communicating with the upper end of the chamber, a valve controlling said communication, and a float connected to said valve and normally holding said valve open and moving the valve to its seat to close off communication between the cylinder and the air chamber when the water rises to a certain level. 65

4. A pump comprising a cylinder, an air chamber communicating with the upper end of the cylinder, a check valve in the discharge of the cylinder, a float valve controlling communication between the cylinder and the air chamber, a draining device connected with the cylinder below the float valve so that the float valve after being closed may automatically open upon the stopping of the pumping action, and means for admitting air to the air chamber upon such draining. 70 75
